UNITED STATES PATENT OFFICE.

GUSTAV A. UNDEEN, OF PROCTOR, VERMONT.

POLISHING-HEAD.

1,035,758.

Specification of Letters Patent. Patented Aug. 13, 1912.

Application filed April 4, 1912. Serial No. 688,503.

To all whom it may concern:

Be it known that I, GUSTAV A. UNDEEN, a citizen of the United States, residing at Proctor, in the county of Rutland and State of Vermont, have invented certain new and useful Improvements in Polishing-Heads, of which the following is a specification.

This invention relates to polishing heads, and more particularly to means for mounting the stones and abrading materials used in the treatment of marble and like materials to impart the proper surface thereto.

The object of the present invention is to so mount the stones in the heads or wheels, that the stones may be held in any position desired, may be easily removed, and may be used for a great length of time.

For a full understanding of the present invention, reference is to be had to the following description and to the accompanying drawings, in which

Figure 1 is a top plan view of the improved polishing head; Fig. 2 is a bottom plan view of the same; Fig. 3 is a modification hereinafter referred to; and Fig. 4 is a central vertical section taken on the line 4-4 of Fig. 2.

Throughout the following detail description and on the several figures of the drawings, similar parts are referred to by like reference characters.

In the drawings, the reference numeral 1 indicates a head or casing which is shown in the form of a wheel having a hub 2, the head or casing 1 affording a mounting for the stones hereinafter referred to. The head 1 is closed on its top side with the exception of the central aperture, and is provided with the ordinary lugs 3. The head or wheel 1 is open on its lower side, and is provided with a series of radial webs 4, which connect the hub 2 with the outer periphery of the wheel or head. On each side of each of the webs 4, a spacing block 5 is provided, which may be secured to the head or wheel in any desired manner, it being immaterial whether the members 5 be constructed of wood or metal, but preferably the former in order to secure lightness of the structure. At about a central position in each quadrant formed by two successive webs 4, a radially disposed wedge shaped block 6 is disposed, these blocks being of the shape shown particularly in Fig. 2 and being constructed of wood or metal. Each block is formed with

an approximately centrally disposed screw threaded bore 7 extending through its interior, and through the bores of each of the blocks 6, a threaded bolt 8 passes. Each of the bolts is provided at its inner extremity with a nut 9, which bears against the hub portion 2, and the bolts are provided at their outer extremities with heads 10 which lie against the outer periphery of the wheel or head 1.

A pair of polishing stones 11 are disposed in each quadrant formed by two successive webs 4, one polishing stone being placed on each side of the wedge shaped block 6 between the latter and the spacing blocks 5. The polishing stones are formed as is shown in Figs. 2 and 4, that is, their operative surfaces 12 and their sides which lie adjacent to the closed side of the wheel or head 1 are parallel, but the two sides 13 converge, as will be seen in Fig. 2. By this arrangement, the converging radial sides of the polishing stones may closely engage the corresponding converging radial sides of the wedge shaped blocks 6.

It will be obvious that as the screw threaded bolt 8 is rotated the bolt being held in a fixed position longitudinally, that the wedge shaped block mounted on the bolt will be moved radially inwardly or outwardly, so as to engage the sides of the adjacent polishing stones, and securely hold the same in place by forcing them against the spacing blocks 5. By this means a very convenient mounting of the polishing stones is obtained. The stones may be easily removed by loosening the wedges 6, and a feature of importance consists in the fact that the stones may be held in any desired vertical position with reference to the wedges, that is to say, as the stones become worn down through continued usage so that their depth is reduced to one-third or one-fourth of their original depth, they may still be firmly secured by means of the wedges, it being necessary that they be engaged by the wedges only to a depth of about one-half an inch. Another advantage of the structure described, resides in the fact that the bolts which move the wedges are operated at the outer periphery of the head or wheel 1, by which provision it is easier to adjust the wedges and it is not necessary by virtue of this construction to have any bolts or nuts on the top side of the head 1, where obviously they would be in a disadvantageous position.

In the modified form of the invention shown in Fig. 3, instead of providing the webs 4 and the adjacent spacing blocks 5, I form a spacing member 14, which will be 5 preferably integrally formed with the body of the head or wheel 1. This obviates the necessity of using the separate spacing blocks 5 and when the polishing stones 11 are in position, they will bear directly 10 against the integral spacing member 14. Another feature of modified construction shown in this figure is, that the bolt-heads are countersunk and for this purpose the outer periphery of the head or wheel 1 is 15 formed with recesses 15 adapted to receive the bolt-heads 10. The latter may be grasped in this position by means of a suitable socket wrench.

Having thus described the invention, what 20 is claimed as new is:

1. A polishing head, comprising a casing, stones adapted for insertion therein, a series of wedges mounted in the casing adapted to engage the stones, spacing blocks disposed 25 between said stones against which the sides of the stones bear, and means for moving the wedges radially inwardly and outwardly, said means being operable at the outer periphery of the casing.
2. A polishing head, comprising a casing, a series of stones disposed in said casing, each of said stones consisting of a solid wedge-shaped block, a series of wedges 30 mounted in the casing, each of said wedges engaging a stone on each converging side thereof, spacing blocks disposed between said stones against which portions of the stones bear, and threaded bolts passing through said wedges to move the same radially inwardly and outwardly.
3. A polishing head, comprising a casing, pairs of stones adapted for insertion therein,

a series of wedges mounted in the casing adapted to engage the stones, means for moving the wedges radially inwardly and 45 outwardly, and fixed spacing blocks disposed between said stones against which the sides of the stones bear.

4. A polishing head, comprising a circular casing, pairs of stones disposed in said casing, a fixed block disposed between each pair of stones and against which one side of each stone bears, a wedge arranged between the stones of each pair and adapted to engage the sides of the stones, and threaded 50 bolts mounted in the said casing and passing through said wedges to move the same radially inwardly and outwardly.

5. A polishing head, comprising a circular casing having a hub and closed at one 60 side, a plurality of polishing stones radially disposed in said casing, each of said stones having two opposite sides converging inwardly, radially disposed wedge shaped blocks disposed between said stones, each 65 adapted to engage the converging sides thereof, a rotatable threaded bolt passing through each of said wedge shaped blocks and through said hub and the outer periphery of the casing to move the said blocks 70 radially inwardly and outwardly, and fixed spacing members arranged between said stones and adapted to engage the sides of the stones not engaged by the wedge shaped blocks, said outer periphery of the casing 75 being formed with recesses adapted to receive the heads of the bolts.

In testimony whereof I affix my signature in presence of two witnesses.

GUSTAV A. UNDEEN.
